Patented Mar. 12, 1957

179,864

ELECTRIC FRYING PAN OR SIMILAR ARTICLE

Donald A. Smith, Wheaton, Ill., assignor to General Electric Company, a corporation of New York

Application May 31, 1956, Serial No. 41,710

Term of patent 7 years

(Cl. D81—10)

FIG. 1

FIG. 2

Fig. 3

Fig. 4

Fig. 1 is a perspective view of an electric frying pan or similar article embodying my new design;

Fig. 2 is a side elevation of the appliance; the opposite side elevation being identical.

Fig. 3 is a top plan view; and

Fig. 4 is a front elevation.

I claim:

The ornamental design for an electric frying pan or similar article, substantially as shown and described.
